UNITED STATES PATENT OFFICE.

JOSEPH W. McLEAN, OF TUCSON, ARIZONA.

SASH-HOLDER.

1,157,318.

Specification of Letters Patent. Patented Oct. 19, 1915.

Application filed July 19, 1915. Serial No. 40,758.

To all whom it may concern:

Be it known that I, JOSEPH W. McLEAN, a citizen of the United States, residing at Tucson, in the county of Pima and State of Arizona, have invented certain new and useful Improvements in Sash-Holders, of which the following is a specification, reference being had to the accompanying drawings.

This invention relates to certain improvements in holders; and it is an object of the invention to provide a novel and improved structure whereby the sash may be maintained in its varying vertical adjustments without the necessity of counter-balancing weights.

The invention consists in the details of construction and in the combination and arrangement of the several parts of my improved sash holder whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be the better understood, I will now proceed to describe the same with reference to the accompanying drawings, wherein—

Figure 1 is a view, partly in elevation and partly in section, illustrating a window structure having a sash holder applied thereto arranged in accordance with an embodiment of my invention; Fig. 2 is a transverse sectional view taken through the device as illustrated in Fig. 1; and Fig. 3 is an enlarged sectional view taken through one of the tubes herein employed.

As disclosed in the accompanying drawings, 1 denotes a window frame of conventional construction having the opposed faces of the vertical stiles thereof provided with the longitudinally disposed tubes 3 formed preferably of rubber and having their peripheries corrugated. The tubes 3 are insertible within vertical grooves provided in the stiles and are substantially entirely confined therein whereby said tubes 50 are effectively maintained against accidental displacement, yet can be removed or replaced with convenience and facility.

4 denotes a sliding sash having in each of

its opposite side faces a mortise 5 adapted to receive the bracket 6 provided with the 55 perforate extension 7 whereby said bracket may be maintained in applied position. The bracket comprises the opposed walls 8 provided with the open slots 9 to removably receive the shaft 10 of the wheel 11, said wheel 60 being provided with a compressible tire 12 preferably of rubber and having its exposed surface corrugated, said tire being engageable with a tube 3, such coaction between the wheel and the tube creating sufficient frictional resistance as to maintain the sash 4 in its various vertical adjustments, in a manner which is believed to be self-evident.

From the foregoing description, it is thought to be obvious that a sash holder 70 constructed in accordance with my invention is of an extremely simple and comparatively inexpensive nature and is particularly well adapted for use by reason of the convenience and facility with which it may be 75 assembled, and it will also be obvious that my invention is susceptible of some change and modification without material departure from the principles and spirit thereof and for this reason I do not wish to be understood as limiting myself to the precise 80 arrangement and formation of the several parts herein shown in carrying out my invention in practice.

I claim:

1. In combination with a window frame and a sliding sash, a tube of compressible material carried by a vertical stile of the frame, and a roller removably mounted in the sash and engageable with the compressible strip of the frame, the periphery of the roller being compressible.

2. In combination with a window frame and a sliding sash, a vertical stile of said frame being provided with a groove, a tube 95 of compressible material positioned within the groove and substantially entirely confined therein, and a roller mounted upon the sash and engageable with the tube, the periphery of the roller being compressible.

In testimony whereof I hereunto affix my signature in the presence of two witnesses.

JOSEPH W. McLEAN.

Witnesses:

RAFAEL PEYSA,
O. E. COMSTOCK, Sr.
